(57) **CLAIM**

The ornamental design for a snowperson-shaped foodstuff, as shown and described.

DESCRIPTION

FIG. 1 is a right-front perspective view of a snowperson-shaped foodstuff, showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a cross-sectional view taken along line 8-8 in FIG. 2; and,

FIG. 9 is a cross-sectional view taken along line 9-9 in FIG. 2.

The dashed lines in the drawing views depict portions of the design that form no part of the claim. Any dashed, unclaimed portion may be removed from the drawings without affecting the scope of the claim.
